EMERGENCY ALARM SYSTEM

William G. Bauer, Brooklyn, Md.

Application January 8, 1942, Serial No. 426,835

1 Claim. (Cl. 177—352)

This invention relates to an emergency signal system and has for an object to provide a system of this character which may be operated independently of current supplied by local electric services in the event of a break down or other failure of current supply due, for example, to bombing in time of war.

A further object is to provide a signal system which can be operated on an emergency power supply including a gasoline engine driven generator for energizing a conventional vacuum tube amplifier, the input of which is supplied by a phonograph and the output of which is in circuit with electrically operated sirens, there being two remote control switch means for interchangeably connecting the conventional service circuit with the amplifier or the emergency gasoline motor driven generator circuit with the amplifier.

A further object is to provide apparatus of this character which will be formed of a few strong, simple and durable parts, which will be inexpensive to manufacture, and which will not easily get out of order.

With the above and other objects in view the invention consists of certain novel details of construction and combinations of parts hereinafter fully described and claimed, it being understood that various modifications may be resorted to within the scope of the appended claim without departing from the spirit or sacrificing any of the advantages of the invention.

In the accompanying drawing forming a part of this specification, the figure is a diagrammatic view showing the different pieces of apparatus and the electrical connections thereof, in accordance with the invention.

Referring to the drawing, 10 designates a plurality of loud speakers which are connected to the output circuit wires 11 and 12 of a vacuum tube amplifier 13. The electric pickup 14 of a conventional electrically driven phonograph 15 is connected by a line 14a to the input circuit wires 16 and 17 of the amplifier. Also a microphone 18 is connected in parallel with the input circuit wires through the medium of circuit wires 19 and 20, there being a manually operable switch 21 connected with the circuit wires 20 and 17 so that the microphone may be energized simultaneously with or independently of the operation of the phonograph to give voice instructions while the phonograph is used as an alarm device, for producing code signals such as are conventionally used during air raids and at the end of an air raid. The amplifier 13 which may be of any

well known construction, is equipped with cut-off switches and other conventional controls. The switches only are shown, and for convenience they are shown as being located in the lines 14a and 44 and are designated 14b and 44b.

The present invention also contemplates energizing the amplifier and the phonograph selectively from a 110 volt local service supply or through the medium of an emergency current supply.

The emergency current supply comprises a gasoline engine 22 for driving a generator 23, on which there is mounted a junction box 24 to which are connected 110 volt circuit wires 25 and 26 as well as circuit wires 27 and 28, one of which is connected to a starting battery for the gasoline engine indicated at 29 and the other which leads to the stationary contact 30 of a solenoid switch 31. The battery is connected by a circuit wire 32 to a circuit wire 33 which is connected to the stationary contacts 34 of remote control switches 35 for selectively closing the battery circuit to start operation of the gasoline engine driven generator, or to utilize the 110 volt service power supply indicated by the circuit wires 36 and 37 for operating the signal system. The movable member of each remote control switch 35 is connected to a common wire 38 to which circuit wires 39 and 40 are connected in parallel, the wire 39 being connected to the movable member of the solenoid switch 31 in the battery circuit while the wire 40 is connected to a fixed switch contact 41 of the switch unit 41a of a change-over relay 42b, the contact 41 being connected by a wire 42 to the coil 31a of the solenoid switch 31, the coil being connected by a wire 43 to the amplifier. When the movable member of either remote control switch 35 is moved to circuit closing position with the fixed battery circuit contact 34, the battery circuit may be traced from the battery 29 to the wire 27, wire 28, closed solenoid switch 31, it being assumed that the service supply has failed, and the solenoid is de-energized, wire 39, wire 38, movable remote control switch member 35, battery switch contact 34, wire 33, wire 32 to the battery, to start operation of the gasoline engine for driving the generator. When the generator starts the coil 31a of the solenoid switch 31 will be energized to open the solenoid switch and open the battery circuit and then current will be supplied from the generator through the wire 29, wire 42, coil 31a of the solenoid switch 31, to hold the switch open, and wire 43, returning from the amplifier through the wire 44, a wire 45 connected to the wire 44,

a stationary contact 46 of the closed switch unit 46a of the change-over relay 42b, which is de-energized when no current flows from the service supply, movable contact 47 of the relay, fixed contact 48 of the switch unit, and aforesaid wire 25 to the junction box 24.

Ordinarily the service current supply will be used for energizing the amplifier and the phonograph, which it will be here pointed out is connected in parallel with the amplifier supply wires 43 and 44 through the medium of wires 49 and 50. For this purpose the service supply wire 37 is connected to the coil 42a of the relay 42b by a wire 51, the coil also being connected by a wire 52 to a wire 53 which is connected to the stationary contact 54 of the switch unit 41a, the wire 53 being connected to the service fixed switch contact 54a of one of the remote control switches 35, this contact being connected by a wire 55 to the service switch contact 54a of the other remote control switch.

When either remote control switch is in circuit closing position to close the service supply at the switch, the service supply circuit may be traced from the wire 36, to the wire 44, amplifier 13, wire 43, solenoid switch 31 to hold the switch open, wire 42, contact 41 of switch unit 41a, wire 40, remote control switch member 35, stationary contact 54a thereof, wire 53, wire 52, coil 42a of the relay 42b and wire 51 to the other service supply wire 37.

In operation, upon the failure of the service current, the solenoid is deenergized which closes the battery circuit which in turn starts the gas engine. The gas engine then drives the generator which supplies the current to the signal.

The operation of the system may be briefly described to be as follows: When the service or main source of current, to which the wires 36 and 37 are connected, is active and the system is in use, the relay switch unit 46a is open as is also the switch 31; the relay switch unit 41a and the switch 46b are closed, and either one or both of the switches 46b and 21 are closed. In the event of failure of this source of current, the change-over relay 42b will be de-energized. This will result in the opening of the switch unit 41a, the closing of the switch unit 46a and the closing of the switch 31. The system is now changed over for operation by the secondary source of current, including the motor-generator unit 22-23. To effect the operation of this unit, one of the remote control switches 35 is operated to close the battery circuit. When this unit is in operation, the switch is opened. The battery circuit includes the operated switch, battery 29, junction box 24 and switch 31. When the secondary source of current becomes active, the

switch 31 opens the battery circuit. The signal system is supplied with current from the secondary source until the main source is again active. To switch over from the secondary source to the main source, one of the remote control switches 35 is operated to engage one of the contacts 54a. This closes the circuit including the wire 31, coil 42 of the change-over relay 42b, wires 52 and 53, the operated remote control switch 35, wires 40, 42 and 43, amplifier 13, wire 44 and switch 44b and wire 36. The closing of this circuit causes the change-over relay 42b to operate in a manner to open the switch unit 46a and close the switch unit 41a, resulting in the changing over from the secondary to the main source of current.

From the above description it is thought that the construction and operation of the invention will be fully understood without further explanation.

I claim:

In an alarm system, the combination with electrically operated signal means, a main circuit including said means and adapted to be connected to a service source of current, a motor-generator unit, a secondary circuit including said unit, a change-over relay embodying first and second switch units interposed respectively in said main and secondary circuits, the coil of said relay being located in said main circuit to maintain said first switch unit closed and said second switch unit opened when the service source is active, a starting circuit for said motor-generator unit, a source of current for said starting circuit, a solenoid switch and a normally opened manually operable switch in said starting circuit, the coil of the said solenoid switch being in said main circuit to maintain said switch opened while the service source of current is active, said first switch unit being adapted to open and said second switch unit being adapted to close on the failure of said source so as to open the main circuit and connect said signaling means to said secondary circuit, said solenoid switch being adapted to close on the failure of said current source so as to permit the starting of the motor-generator unit on the closing of said manually operable switch, said solenoid switch again opening on the operation of said unit, and a circuit connected to said main circuit and to the coil of the relay and said manually operable switch so as to effect the opening of said second switch unit and the closing of said first switch unit when said manually operable switch is closed on the restoration of the service source of current and thus disconnect said signal means from said secondary circuit and close said main circuit.

WILLIAM G. BAUER.
